UNITED STATES PATENT OFFICE

2,408,036

ELECTROLYTIC PINACOL PRODUCTION

Charles R. Boettger, Jr., Roselle, Thomas S. Chambers, Newark, and Ober C. Slotterbeck, Rahway, N. J., assignors to Standard Oil Development Company, a corporation of Delaware

Application July 11, 1942, Serial No. 450,518

6 Claims. (Cl. 264—77)

1

The present invention pertains to a method of preparing vicinal glycols by electrolytic reduction of ketones and generally to all types of carbon to carbon reductive condensation reactions.

Specifically, this invention is concerned with the reduction of acetone electrolytically to tetramethylethylene glycol.

It is the object of the present invention to provide the art with a novel and highly advantageous method of electrolytically forming vicinal glycols and especially pinacols from the corresponding ketones, and also to provide the art with novel electrodes for effecting the reduction of organic compounds.

The electrolytic reduction of ketones can take place at the cathode surface according to any one of the following reactions:

Other side reactions result in the formation of metal alkyls, especially when the reduction is effected in acid medium with lead cathodes.

An electrolytic method for effecting the reductive condensation reaction whereby acetone is converted to pinacol (tetramethylethylene glycol) using a lead cathode and an acid catholyte is described in German Patent 113,719 (1899).

Several German patents pertaining to the electrolytic reduction of acetone to tetramethylethylene glycol were issued in the period 1912-1920. Among these patents were D. R. P. 306,304 (1917), 306,523 (1918) and 324,919 (1920). The principal developments made in this period appear to have been the use of mixed metal and alloy cathodes, such as 4 to 10% copper-96 to 90% lead mixtures and 10% tin-90% lead alloy and the use of horizontally suspended cathodes to prevent the metal alkyls formed from accumulating on and decreasing the activity of the electrode surface.

All of the prior processes for electrolytically

2

converting acetone to pinacol have been unsatisfactory either because pinacol current efficiency or the overall current efficiency or both were too low.

It has now been found that the formation of toxic lead alkyls which diminish the effectiveness of the cathode can be minimized and the reduction of ketones to vicinal glycols effected with good current efficiency and high ratio of glycols to other reduction products by utilizing cathodes, the surfaces of which contain about 30-80% of copper or other metal of similar low hydrogen overvoltage and about 70-20% of lead.

The cathodes in accordance with the present invention may be prepared in various ways. The simplest procedure would involve merely mixing finely divided lead and copper in the desired proportion and compressing the mixture into sheets of the desired dimensions. Alternatively the cathodes could be prepared by coating lead particles with copper and subjecting a mass of such coated particles to high pressure and possibly to a heating or sintering treatment. This procedure yields a copper matrix in which lead particles are evenly distributed. By reversing the procedure and using copper particles coated with lead it is possible to obtain a lead matrix with copper particles uniformly distributed therein.

Substantially the same results are obtained if only the surface of the cathode corresponds to the above composition. Such cathodes can be made simply by forcing metal powder, wire strands, screening or the like of low hydrogen overvoltage metals into the surface of a lead sheet under heavy pressure. Instead of copper powder, screening, or the like, one may also use other metals of low hydrogen overvoltage or alloys such as nickel, brass or Monel metal.

The ketones which may be treated in accordance with the present invention correspond to the general formula

wherein the R stands for a member of the group consisting of alkyl and aryl radicals and alkyl and aryl radicals substituted by a group which is not reducible under the conditions employed i. e., halogen, carboxyl, etc. Such ketones include, for

example, acetone, methyl ethyl ketone, diethyl ketone, methyl propyl ketone, ethyl propyl ketone, acetophenone, and benzophenone.

By using mixtures of different ketones, it is possible to prepare certain mixed glycols. For example, acetone may be condensed with methyl ethyl ketone to form the glycol corresponding to the formula

or methyl ethyl ketone may be condensed for example with acetophenone to form the glycol

The glycols formed in accordance with the present invention correspond to the general formula:

wherein each R stands for an alkyl or aryl radical or an alkyl or aryl radical substituted by a substituent such as halogen, carboxyl, etc.

A cell suitable for carrying out the reduction of ketones in accordance with the present invention is shown diagrammatically in the accompanying drawing. The single unit cell shown consists of a rectangular jar or the like b arranged in a cooling bath a. An anode e of lead or the like is arranged inside an acid resistant diaphragm d, which divides the cell into an anode and cathode compartment. As shown, two cathodes c of the composition indicated above are arranged in the cell.

The details of the cell are not critical to our invention and the cell may be altered in numerous ways. For example, a number of cells could be combined in a single tank and if desired the process could be carried out continuously by providing a circulating pump, an overflow means for drawing off the electrolyte from the cell, means for separating electrolysis products from the withdrawn catholyte and means for making the electrolyte up to initial strength for re-introduction into the cell.

The use of a diaphragm is recommended since the products formed at the cathode are liable to be oxidized at the anode. The use of a diaphragm may be avoided if desired by the use of anolyte and catholyte of unequal densities in cells provided with horizontal electrodes, the use of a high anodic current density or by the use of anodes having a low oxygen overvoltage, i. e., nickel or by a combination of two or more of these expedients.

Aside from the nature of the cathode surface, the factor which has the greatest effect upon the course of the reaction in the cell is the concentration and type of electrolyte used. Acid media have given the best results. The ratio of ketone to water in the catholyte should be high. However, a ratio of 4/1 appears to be approximately the upper limit economically because of the high resistivity of the solution which would greatly increase the power cost. In the production of tetramethylethylene glycol the preferred

catholyte is one containing about 4 volumes of acetone for each volume of sulfuric acid of about 20 per cent strength. The acid, however, may vary in strength between about 10 per cent and about 40 per cent.

The anolyte may be a sulfuric acid solution of about 10 to 40 per cent strength. The electrolyte is preferably maintained at temperatures between about 0° C. and about 25° C. The current density applied may vary between about 0.1 and about 4 amperes/sq. dm., the preferred current density being within the range of about 1.5 to about 2 amperes/sq. dm.

The following examples serve to illustrate our invention but it is to be understood that our invention is not limited thereto.

Example 1

576 cc. of a 4/1 acetone-10 per cent sulfuric acid solution were placed in the cathode compartment of a cell as shown in the drawing. The anolyte used was 10 per cent sulfuric acid and the anode was lead. The cathodes used contained 60% copper and 40% lead.

Electrolysis was effected at about 16° C. at a current density of 1.67 amps./sq. dm. and at 5.4 volts. The run was continued for 4 hours and a total of 11.2 ampere hours were supplied to the cell. Upon conclusion of the electrolysis the catholyte was stripped of isopropyl alcohol and unreacted acetone and pinacol (tetramethylethylene glycol) was separated as the hexahydrate by cooling and filtering the stripped catholyte. 8.0 grams of pinacol hydrate and 2 grams of isopropyl alcohol were obtained corresponding to a current efficiency based upon pinacol of 17%. The mole ratio of pinacol to isopropyl alcohol was 1/1.

Example 2

3430 cc. of 4/1 acetone-10 per cent sulfuric acid solution were placed in the cathode compartment of a single unit cell as shown in the drawing. The anolyte used was 10 per cent sulfuric acid and the anode was lead. The cathodes used were prepared by rolling copper gauze under pressure onto lead sheets. Rough measurement indicated that the surface consisted of about 70% of copper and 30% of lead.

The electrolysis was effected at about 16° C. at a current density of about 0.84 amp./sq. dm. and at 6.2 to 7 volts. The run was continued for 6 hours and a total of 40.2 ampere hours were supplied to the cell. Upon conclusion of the electrolysis the catholyte was treated as described in Example 1 to separate the pinacol hydrate. 42.9 grams of pinacol hydrate and 11.2 grams of isopropyl alcohol were obtained corresponding to a current efficiency based upon pinacol of 25.3% and a current efficiency based upon isopropyl alcohol of 25%. The mole ratio of pinacol to isopropyl alcohol was 1/1.

Example 3

2340 cc. of a 4/1 acetone-25 per cent sulfuric acid solution were treated in a cell similar to that used in the foregoing examples. The anolyte was 25 per cent sulfuric acid and the anode was lead. The cathodes were prepared by compressing 20 mesh copper wire screen into a lead sheet. Rough measurements gave about 40% lead and 60% copper on the exposed surface of the cathode.

The electrolysis was effected at about 16° C. and a current density of about 1.67 am./sq. dm. and at 5.8 to 6.8 volts. The run was continued for 5 hours.

A comparison run was made in a similar cell with the same volume and strength of catholyte and with a lead anode. The cathode used was a mixture containing 4% copper and 96% lead. The electrolysis was effected at about 16° C. at a current density of 2.0 amps./sq. dm. and at 6.3 to 7.8 volts.

The results of both of the foregoing runs are summarized in the following table:

	Time, hrs.	Amp. hrs., total	Pinacol hydrate (grams)		Isopropyl alc. (grams)		Pinacol C. E.		Isopropyl alc. C. E.		Mol ratio pinacol/ isopropyl alcohol
			Total	Interval ¹	Total	Interval ¹	Total	Interval ¹	Total	Interval ¹	
60% Cu 40% Pb-----	2	20	21.3	21.3	5.2	5.2	25.2	25.2	23.5	23.5	1.08/1
	4	40	40.0	18.7	8.9	3.7	23.7	22.2	19.9	16.5	1.2/1
	5	50	56.5	16.5	11.5	2.6	26.9	39.4	20.8	23.2	1.3/1
4% Cu 96% Pb-----	2	24	6.3	6.3	-----	-----	6.2	6.2	-----	-----	-----
	4	48	17.5	11.2	-----	-----	8.7	11.1	19.5	19.5	0.47/1
	6	72	28.3	10.8	15.8	-----	9.3	10.6	-----	-----	-----

¹ Readings and analysis were made at the stated time intervals given.

No lead alkyls were formed with the cathode having the copper screening rolled thereon but large amounts of lead alkyls were formed and coated the surface of the 4% copper, 96% lead cathode.

We claim:

1. In the process of producing glycols corresponding to the general formula

wherein R stands for a member of the group consisting of alkyl and aryl radicals and substituted alkyl and aryl radicals by the electrolytic reduction of an aqueous acid solution of a ketone of the formula

wherein R stands for a member of the group consisting of alkyl and aryl radicals and alkyl and aryl radicals substituted by a group which is not reducible under the reaction conditions employed the improvement which comprises effecting said reduction in a diaphragm cell in contact with a cathode consisting of from 60 to 80% of copper and 40 to 20% of lead at a temperature below about 25° C. and at a current density of between about 0.1 and about 4 amperes per sq. dm.

2. In the process of producing glycols corresponding to the general formula

wherein R stands for a member of the group consisting of alkyl and aryl radicals and substituted alkyl and aryl radicals, by the electrolytic re-

duction of an aqueous sulfuric acid solution of a ketone of the formula

wherein R stands for a member of the group consisting of alkyl and aryl radicals and alkyl and aryl radicals substituted by a group which

is not reducible under the conditions employed the improvement which comprises effecting said reduction in a diaphragm cell in contact with a cathode consisting of from 60 to 80% of copper and from 40 to 20% of lead at a temperature below about 25° C. and at a current density of between about 0.1 and about 4 amperes per sq. dm.

3. The process as defined in claim 2 wherein the ketone and sulfuric acid are used in the ratio of about 4 volumes of ketone to 1 volume of acid.

4. In the process of preparing tetramethyl ethylene glycol by the electrolytic reduction of an aqueous acid solution of acetone the improvement which comprises effecting the reduction in a diaphragm cell in contact with a cathode consisting of from about 60 to 80% of copper and 40 to 20% of lead at a temperature below about 25° C. and at a current density of between about 0.1 and about 4 amperes per sq. dm.

5. In the process of preparing tetramethyl ethylene glycol by the electrolytic reduction of an aqueous sulfuric acid solution of acetone the improvement which comprises effecting the reduction in a diaphragm cell in contact with a cathode consisting of from about 60 to 80% of copper and 40 to 20% of lead at a temperature below about 25° C. and at a current density of between about 0.1 and about 4 amperes per sq. dm.

6. In the process of preparing tetramethyl ethylene glycol by the electrolytic reduction of a solution of about 4 volumes of acetone in about one volume of aqueous sulfuric acid of about 20% strength the improvement which comprises effecting the reduction in a diaphragm cell in contact with a cathode consisting of from about 60 to 80% of copper and 40 to 20% of lead at a temperature below about 25° C. and at a current density of between about 0.1 and about 4 amperes per sq. dm.
